CLAIM

The ornamental design for a hanger, as shown and described.

DESCRIPTION

FIG. 1 is a top plan view showing my new design of a hanger;

FIG. 2 is a bottom plan view of the hanger;

FIG. 3 is an end view thereof;

FIG. 4 is an enlarged side view thereof;

FIG. 5 is an opposite side view with the tongue in an extended position;

FIG. 6 is an enlarged sectional view taken along line 6—6 of FIG. 1; and,

FIG. 7 is a top side perspective view of the hanger.
